UNITED STATES PATENT OFFICE.

VOLNEY W. MASON, JR., OF HYDE PARK, MASSACHUSETTS.

VICE FOR MILLING-MACHINES OR PLANERS.

SPECIFICATION forming part of Letters Patent No. 508,732, dated November 14, 1893.

Application filed January 16, 1893. Serial No. 458,570. (No model.)

To all whom it may concern:

Be it known that I, VOLNEY W. MASON, JR., a citizen of the United States, residing at Hyde Park, in the county of Norfolk and State of Massachusetts, have invented a new and Improved Vise for Milling-Machines, Planers, &c., of which the following is a specification.

This improved vise is intended particularly for use in connection with milling machines, but there are other machines to which it may be applied, such as planers; and I propose to use it in connection with any machine where it will be of service.

Vises for milling machines as ordinarily constructed have two jaws or clamps, one having a limited movement with relation to the other, and the capacity of the vise is confined to the very limited movement of this movable jaw.

In my improvement, the capacity of the vise is very greatly enhanced as is also the length and nicety of the adjustment of the parts upon the bed of the milling or other machine.

In the accompanying drawings, in which similar letters of reference indicate like parts, Figure 1 is a perspective view of my improved device secured to the bed of the milling machine. Fig. 2 is a central longitudinal vertical section of the same. Fig. 3 is a detail in plan and horizontal section, illustrating the operation of the holder for irregular pieces.

A represents portions of the frame of the milling machine and A' the table secured thereto, upon which table is the bed B of the vise. This bed is provided with, say, three, longitudinal parallel grooves B' of the T shape shown, and, say, four transverse intersecting parallel grooves B'' of substantially the same shape.

C represents one of the jaws or clamps of the vise, and may be considered as that which takes the place of the stationary jaw in the ordinary vise. It is not however, in fact, stationary, but is secured by bolts D and nuts D' to the bed, the heads of said bolts lying in the wings of the grooves B' and the nuts serving to secure the jaws C in any desired position, whether near to or remote from the right hand edge of the bed. This jaw is provided with the face-plate C' secured thereto

by the screws C''. E is the other jaw of the vise provided with the face-plate E' secured thereto by screws E''. This jaw is also movable and takes the place of the ordinary movable jaw and is secured adjustably upon the bed by means of bolts F whose heads lie in the wings of the grooves B', said bolts being secured by nuts F' and extending through longitudinally elongated slots e in the jaw E.

H is a sliding block adjustably secured to the bed by means of the bolts I and nuts I' in exactly the same manner as the jaws C E. A screw or bolt K extends into a correspondingly threaded horizontal opening L in the rear end of the jaw E, said screw being provided with a smooth portion K' which extends through a smooth horizontal bore in the sliding block H, and is held therein by a shoulder K'' and the head K'''.

It will readily be seen that the limit of the range or capacity of this vise is the limit of the length of the bed to which the jaws are secured, inasmuch as the jaw C can be secured at the extreme right hand end of the bed, the block H at the extreme left hand end, and the jaw E drawn by the bolt K close to the block H. The adjustments consist, first, of the movement of the jaw C longitudinally on the bed, second, of the movement of the block H on the bed, third, the movement of the jaw E with relation to the block H produced by the bolt K, and fourth, the movement of the jaw E allowed by the elongated slots e.

P is a holder or supplemental jaw intended to accommodate irregular or non-rectangular pieces or articles. This holder P which may be of any desired thickness as shown in the three figures, has a rearward extension or knuckle P' which extends horizontally into a concavity or groove R in the plate E' (see Fig. 3). An irregular piece clamped between the jaws E and C would therefore cause the holder or supplemental jaw P to turn or swing horizontally, as shown by broken lines in Fig. 3, and conform to the angle of one side of the piece being held. A flange or shoulder P'' provides a corner for holding the piece and preventing it from slipping out horizontally, and as the groove R does not extend quite to the top of the plate E', an

overhanging lip R' is produced, which prevents the piece from jumping vertically.

The jaws C E and block H can be readily removed at any time if desired, by means of 5 the transverse grooves B''.

Having thus fully described my invention, what I claim, and desire to secure by Letters Patent, is—

1. In a vise, the combination of the jaw E 10 provided with the vertical groove R, said groove or recess extending into the face of the jaw below its upper surface but not breaking the face line of said jaw at its upper edge, and the swinging holder or supplemental jaw P provided with the knuckle P' for 15

loosely resting in said groove, substantially as set forth.

2. In a vise, the combination with the jaw E provided with the groove or recess R, of the swinging holder or supplemental jaw P 20 loosely pivoted in said recess and provided with the flange or shoulder P'' at one end, whereby a corner is furnished for holding a non-rectangular piece of stock and preventing it from slipping horizontally, substantially as set forth. 25

VOLNEY W. MASON, JR.
